Frank K. Kent

UNITED STATES PATENT OFFICE.

HERMAN E. S. CHAYES, OF NEW YORK, N. Y.

REMOVABLE DENTURE.

Application filed August 26, 1921. Serial No. 495,613.

To all whom it may concern:

Be it known that I, HERMAN E. S. CHAYES, a citizen of the United States, residing at New York, in the county of New York and State of New York, have invented certain new and useful Improvements in Removable Dentures, of which the following is a specification.

This invention relates to removable dentures of the general type described in Patent No. 1,366,058, Jan. 18, 1921.

The objects of the present invention are, as in the invention described in the patent referred to, to provide a removable dental bridge member which is capable of slight movement under the stress of mastication, which can be made up of interchangeable standardized parts, and in which the connecting means between the bridge and its supporting piers form an actual part of the occlusal surface of the dental arch.

A further object of the invention is to provide a tongue and socket connecting means in which the socket does not open to the occlusal surface but is covered by a dental member forming part of the connecting means.

I have found that by providing downwardly extending sockets in seats inlaid in the lower part of the bridge-facing sides of the pier teeth, the sockets can be overlaid or covered by artificial denture members rigidly connected at one side to the terminal teeth of the bridge work, each denture member having a tongue extending downwardly from its lower face for engagement with a socket. Preferably the denture members included in the connecting means are formed to replace the portions of the pier teeth which were removed in seating the socket members. This and other features of the invention will be hereinafter more particularly described.

In the drawings, in which a preferred embodiment of the invention has been selected for illustration—

Figure 1 is a view in perspective of a dental arch in which is included a removable bridge member embodying the invention.

Figure 2 is a detail view partly in side elevation and partly in section showing the means for connecting the bridge member to the pier teeth.

Figure 3 is a plan view of a bridge-supporting or pier tooth, fitted with a socket member forming part of the invention.

Figure 4 is a vertical section of the pier tooth shown in Figure 3.

Figure 5 is a view in end elevation of a dental bridge member equipped with means for connecting the bridge member to a pier tooth.

Figure 6 is a plan view of the device shown in Figure 5.

Figure 7 is a view in side elevation of the device shown in Figure 6.

Figure 8 is a view of a modified form of tongue shown in position in a socket member illustrated in section.

Referring to the drawings for a more detailed description, a complete dental arch is shown at 5 in Figure 1 in which is included a removable bridge member 7 made up of two artificial teeth 9 mounted on a base or saddle 11 formed of gold or other suitable material. The bridge teeth 9 are provided respectively with connecting members 12 which are in turn provided with laterally extending anchoring lugs 13 that are embedded in the adjacent lateral faces of the bridge teeth, as is best shown in Figures 6 and 7 of the drawing. The members 12 are also provided with lugs or tongues 15 projecting downwardly from the under sides thereof as is indicated in Figures 5 and 7 of the drawing.

A suitable socket member for receiving the tongue 15 takes the form of a seat 17 mounted in the bridge-facing side of a pier tooth 19, as indicated in Figures 2 and 4 of the drawing. The seat 17 consists of a block 90 of suitable non-corrosive metal having a relatively horizontal surface or shelf 21 formed in a plane intermediate the gum and the operating surface of the tooth, the surface 21 serving as a seat on which to receive the member 12. A socket 23 entering the member 17 from the surface 21 receives the tongue 15 as indicated in Figure 2 and serves to anchor or hold the bridge member in its place.

The tongue 15 and the slot 23 have, as will be seen, a relatively thin or flat formation along the row of teeth and a relatively wide or elongated construction transverse to the row. This produces an exceedingly staple anchoring effect so far as concerns longitudinal movement of the bridge in its seat but permits a slight up and down movement of the bridge and even a slight lateral rocking movement of the bridge structure. The lat-

ter function is facilitated by forming rounded corners on the tongue 15 as at 25 in Figure 5 of the drawing. This effect may be still further enhanced where desired by removing a small amount of metal from the opposite edges of the tongue at its point of emergence from the member 12, as at 27 in Figure 8. In order to provide a wear piece for the outwardly facing surface of the member 12, the socket member 17 is preferably provided with an upwardly extending abutment member 29 which also assists in the inlaying or anchoring of the socket member in the pivot tooth structure.

15 It will be seen that an effective connecting means between the bridge member and the supporting or pivot tooth has been provided in which the connecting member itself forms a dental member.

20 What is claimed is:

1. In a device for connecting dental bridge members to supporting parts, a seat mounted in a tooth structure and having a supporting surface substantially parallel to the occlusal surface of the dental arch, a dental member forming the terminal member of a bridge structure and formed to rest on the supporting surface of the seat, said dental member and said seat having a separable tongue and socket connection, said dental member having an occlusal surface in the plane of the occlusal surface of the arch, and said dental member being rigidly attached to a lateral face of the next adjacent tooth of the bridge structure.

2. In a device for connecting dental bridge members to supporting parts, a seat mounted in a tooth structure and occupying a substantial part of the horizontal cross-section thereof, said seat having a supporting surface substantially parallel to the occlusal surface of the dental arch and an elongated socket extending into the seat from said surface, a dental member formed to rest 45 on the supporting surface of the seat, the seat-engaging surface of said dental member having a tongue fitting said elongated

socket, said elongated socket and tongue extending transversely of the dental arch, and a rigid connection between the dental member and the adjacent face of the next adjacent tooth in the bridge structure.

3. In a device for connecting dental bridge members to supporting parts, a seat mounted in a tooth structure and having a supporting surface substantially parallel to the occlusal surface of the dental arch, said seat having an elongated socket extending therein from the supporting surface, a dental member formed to engage said supporting surface in covering relation to said slot and provided with a tongue member fitting into the slot, said tongue and slot extending transversely of the dental arch and formed to permit slight rocking movement of the engaged parts, and a rigid connection between the dental member and the bridge structure.

4. In a device for connecting dental bridge members to supporting parts, a seat mounted in a tooth structure and occupying a substantial part of the horizontal cross-section thereof, said seat having a supporting surface substantially parallel to the occlusal surface of the dental arch and intermediate the gum and the occlusal surface, said seat having an elongated socket member extending therein from the supporting surface, a dental member formed to engage said supporting surface in covering relation to said slot and provided with a tongue member fitting into said slot, said tongue and slot extending transversely of the dental arch and formed to permit slight rocking movement of the parts transversely to the arch, an abutment member on said seat and extending to the occlusal surface of the tooth structure for endwise engagement by said dental member, and a laterally extending lug on said dental member anchored in the adjacent face of the next adjacent tooth in the bridge structure.

In testimony whereof I affix my signature.

HERMAN E. S. CHAYES.
